US0D1091082S

(12) **United States Design Patent** (10) Patent No.: **US D1,091,082 S**
(45) Date of Patent: ** Sep. 2, 2025

(54) **FOOTWEAR MIDSOLE**

- (71) Applicant: **adidas AG**, Herzogenaurach (DE)
(72) Inventors: **Stephen P. Dobson**, Nuremberg (DE);
Moritz Hoellmueller, Fuerth (DE)
(73) Assignee: **adidas AG**, Herzogenaurach (DE)
(**) Term: **15 Years**
(21) Appl. No.: **29/949,593**
(22) Filed: **Jun. 27, 2024**

Related U.S. Application Data

- (63) Continuation of application No. 29/813,937, filed on Nov. 2, 2021, now Pat. No. Des. 1,039,804, which is a continuation of application No. 29/721,029, filed on Jan. 17, 2020, now Pat. No. Des. 938,154.

Primary Examiner — T Chase Nelson*(74) Attorney, Agent, or Firm* — Kilpatrick Townsend & Stockton LLP(57) **CLAIM**

The ornamental design for a footwear midsole as shown and described.

DESCRIPTION

The sole FIGURE is a side view of a footwear midsole showing our new design. The dash-dot-dash lines define the boundaries of the claimed design, and the dash-dot-dash lines and portions of the footwear midsole outside these unclaimed boundaries form no part of the claimed design.
